Hanson & Hanson

Patented Dec. 12, 1922.

UNITED STATES PATENT OFFICE.

ARTHUR C. ROWLEY, OF PHILADELPHIA, PENNSYLVANIA, ASSIGNOR TO GLOBE
AUTOMATIC SPRINKLER COMPANY, OF PHILADELPHIA, PENNSYLVANIA, A
CORPORATION OF PENNSYLVANIA.

FIRE-EXTINGUISHING APPARATUS.

Application filed September 14, 1913. Serial No. 254,130.

To all whom it may concern:

Be it known that I, ARTHUR C. ROWLEY, a citizen of the United States, residing in Philadelphia, Pennsylvania, have invented 5 Fire-Extinguishing Apparatus, of which the following is a specification.

My invention relates to that class of apparatus or systems in which the opening of an automatic sprinkler and the consequent 10 release of fluid from the pipe to which it is attached causes operation of certain apparatus and the consequent delivery from the sprinkler of a fire extinguishing fluid such as carbonic acid gas.

One object of the invention is to provide a system of the general class above indicated which shall be more certain in its action than those previously installed;—the invention 15 contemplating the employment of a relay apparatus, actuated upon the escape of fluid from the system, whereby a main apparatus is put in operation, with a consequent delivery to the open sprinkler of the fire extinguishing fluid.

It is further desired to provide a fire extinguishing system which in addition to the above noted features, shall be relatively simple and substantial as to the number and arrangement of its parts and consequently not only relatively inexpensive to 20 install and maintain but practically certain and quick in its operation under predetermined conditions.

These objects and other advantageous ends I attain as hereinafter set forth, reference being had to the accompanying drawings, in which,

The figure is a diagrammatic elevation, partly in section, illustrating one arrangement of the apparatus constituting my invention.

In the above drawing 1 represent a main tank having the capacity necessary for holding the main body of soda solution for 45 the system and from the lowest portion of this tank extends a riser 2 having any desired and suitable number of branches 3 extending laterally from it, usually immediately under the ceiling of each story of 50 the building in which the system is installed. The various temperature respon-

sive devices such as automatic sprinklers 4 are connected to these branches in the customary manner.

In the present instance the riser 2 has 55 a continuation 5 extending from its highest point to a vertically elongated expansion tank 6, suitably mounted at the highest part of the system and the lower part of the riser has connected in it a dry pipe or check 60 valve 2^a whereby the fluid contained in it and in its branches is separated from the liquid within the tank 1. The necessary amount of acid required to properly act on the volume of soda solution in the tank 1 65 is contained in a holder 7 preferably having a non-corrodible lining 8, and connected to said tank through a lead lined pipe 9 running from its lowest part through a stuffing box 10 into the top of said tank.

In order that the main body of acid contained in the holder 7 shall certainly be discharged into the tank 1 upon the opening of one of the sprinklers, I provide an auxiliary or relay soda tank 11 whose lowest 70 portion is connected through a pipe 12 with the lowest portion of a small tank mounted adjacent thereto whose top is connected through a pipe 13 with the topmost portion of the expansion tank 6. Preferably adjacent the small tank 14, there is connected in the conduit 13 a check valve 15 having a soft metal seat and designed to normally remain open though capable of closing to prevent flow of liquid from the tank 14 up 75 through the pipe 13.

The auxiliary soda tank 11 has its upper part connected through a pipe 16 to the uppermost part of the main acid holder 7 and has mounted within it a lever 17 preferably 80 of the first order, fulcrumed on suitable knife edges or pivots supported by the sides of said auxiliary tank.

One arm of this lever has connected to it a float 18 and the other is designed to engage an auxiliary acid holder 19 preferably made of glass or stoneware, and provided with trunnions or pivots 20 whereby it is normally so carried as to remain resting against one side of the tank 11 with its 95 discharge opening uppermost. Said opening is normally closed by a suitable loose

cap and the second arm of the lever 17 has connected to it a link or extension 21 designed to be capable of tipping said holder past its position of unstable equilibrium and 5 causing it to discharge its contents into the soda solution within the auxiliary soda tank 11, whenever said lever arm is forced up by the lowering of the float 18.

The highest part of the auxiliary tank 11 10 is provided with a vent pipe 22 terminating in a soft seat check valve 23 so mounted as to be normally open although free to close to prevent escape of fluid through the pipe 22 whenever the pressure within the 15 auxiliary tank 11 rises above the normal. Said tank is also preferably provided with a pressure gauge 24.

In order to charge my system an inert 20 liquid having a low freezing point such as calcium chloride, is introduced into the riser 2 by any suitable means such as through a branch pipe 25 and the system is filled sufficiently to cause such liquid to enter the lower part of the expansion tank 25 6;—the cock 26 being opened to allow escape of the air. The main charge of soda solution is then introduced into the main soda tank 1 and an auxiliary charge is likewise placed in the auxiliary soda tank 11 30 and reservoir 14, which are filled sufficiently to buoy up the float without causing it to affect the holder 19. The main acid charge is then placed in the vessel 7 and the auxiliary acid charge is placed in the auxiliary holder 19 which is mounted on its pivots within the tank 11 so that its discharge opening is uppermost.

Under conditions of use when one of the 40 sprinklers 4 opens by reason of a predetermined rise of temperature such as would be caused by a fire in its vicinity, the liquid in the upper part of the riser and in the lower part of the expansion tank 6 is discharged under the action of gravity from said 45 sprinkler. The lowering of the liquid level in the expansion tank 6 exhausts the air from the pipe 13 and from the upper part of the reservoir 14, so that, owing to the suction produced there is an immediate flow of the 50 soda solution from the auxiliary soda tank into this reservoir. The consequent lowering of the level of the soda charge in the auxiliary soda tank permits the float 18 to fall and causes the long arm of the lever 17 to act upwardly through the link 21 to tip 55 over the auxiliary acid holder, which thereupon delivers its acid into the auxiliary soda charge of said auxiliary tank. The immediate generation of carbon dioxide resulting 60 from the action of the acid on the soda results in the production of a high pressure in the auxiliary soda tank whereupon the check valves 15 and 23 are closed and there is a flow of high pressure gas into the top 65 part of the main acid holder 7. The acid in

this holder is at once certainly and forcibly expelled through the pipe 9 into the main soda tank 1, with the resulting generation of a large volume of high pressure carbon dioxide, which flows through the riser 2 and 70 is delivered to the particular automatic sprinkler which originally opened.

As a result of this rapid delivery of a relatively large volume of non-combustible gas, the fire in the vicinity of the open sprinkler 75 is at once extinguished, where if the flow of liquid resulting from the opening of the sprinkler was depended upon to cause delivery of the main acid charge into the main soda tank, the result would have been uncertain, owing to the small amount of energy 80 resulting from the opening of a sprinkler. If however, between the apparatus containing the main acid and soda charges and the sprinkler system there be introduced a relay 85 device operative upon the flow of fluid or change of pressure resulting from the operation of one or more of the sprinklers, such device by generating what is in effect an explosive body of gas which insures the rapid 90 and complete delivery of the main charge of acid to the main soda solution, makes the operation of the system certain, effective and rapid.

I claim:

1. The combination in a fire extinguishing system of a supply pipe having sprinklers; a main soda tank; a main container for acid associated therewith; an auxiliary soda tank connected to said main acid container; an auxiliary acid container; a pipe connecting the auxiliary soda container with the supply pipe; and a float within the auxiliary soda tank operative to cause discharge of acid from the auxiliary acid container into the auxiliary soda tank when a change of level therein causes a predetermined alteration in the position of the float. 95

2. The combination of a supply pipe having 110 sprinklers; a main soda tank; a main acid holder connected to said tank; an auxiliary soda tank connected to deliver fluid into the main acid holder to force the acid therefrom into the main soda tank; an auxiliary acid holder movably supported in said 115 auxiliary tank; a float in said latter tank for controlling the position of the auxiliary acid holder; and a pipe connecting the auxiliary soda tank with the sprinkler system.

3. The combination of a supply pipe having 120 sprinklers; an elevated expansion tank connected to the supply pipe; a generator of fire extinguishing fluid connected to the supply pipe; a gas generator connected to said first generator and including a controlling 125 float and a liquid-containing casing therefor; with a pipe connecting said casing and the expansion tank.

4. The combination of a supply pipe having 130 sprinklers; an elevated expansion tank

connected to the supply pipe; a main generator of fire extinguishing fluid connected to the supply pipe and including a main acid holder; an auxiliary generator including a tank connected to discharge gas under pressure into the acid holder, an auxiliary acid holder and a float in said tank connected to

cause delivery of acid from the latter holder upon a predetermined change of liquid level in the tank; and a pipe connecting the latter tank to the expansion tank.

In witness whereof I affix my signature.

ARTHUR C. ROWLEY.
